AUTOMATIC CIRCUIT BREAKER

John Hilmar Helland, Newark, Ohio, assignor of
one-third to William M. Pearson, Newark,
Ohio

Application January 25, 1940, Serial No. 315,608

5 Claims. (Cl. 200—106)

This invention relates to an automatically controlled circuit breaker, designed for use in the usual fuse plug socket of an electric line, the primary object of the invention being to provide means for breaking the circuit in which the device is located, when a short or overload occurs in the circuit, thereby protecting the circuit and appliances connected therein.

An important object of the invention is to provide a device of this character which may be readily reset after it has operated to break the circuit, and after the defective line or appliance has been repaired, thereby eliminating the necessity of installing a new circuit breaker in the circuit.

Another important object of the invention is to provide a device of this character including a stationary contact and a movable contact, the movable contact being positioned and constructed in such a way that it will snap into engagement with the stationary contact, completing the circuit, thereby eliminating any possibility of arcing, when the movable contact member engages the stationary contact member.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a longitudinal sectional view through a device constructed in accordance with the invention.

Figure 2 is a sectional view taken on line 2—2 of Figure 1.

Figure 3 is a sectional view taken on line 3—3 of Figure 1.

Figure 4 is a sectional view taken on line 4—4 of Figure 1.

Figure 5 is a sectional view taken on line 5—5 of Figure 4.

Figure 6 is a sectional view through the device illustrating the movable contact member as in its inactive position.

Figure 7 shows a detail of the casing structure.

Figure 8 is a sectional view taken along line 8—8 of Figure 7.

Referring to the drawings in detail, the reference character 5 designates the shell or body portion of the circuit breaker which is formed with

5 a reduced end portion 6 formed with threads to accommodate the screw sleeve 7 that has an inwardly extended annular flange 8 formed at the lower end thereof. This annular flange provides a support for the insulating member 9, through which the contact wire 10 extends, the wire 10 being connected with the solenoid coil 11 mounted within the reduced end portion of the shell or body portion 5.

10 The coil 11 is mounted on the spool-like support 12, and is secured in position by means of the screw 13 which is shown as extended through the plate 14 that closes the lower end of the reduced portion 6.

15 Mounted within the support 12, is a coiled spring indicated at 15 which is of the contractile type, the lower end of the spring being secured to the support 12, at 16. The upper end of the spring 15 is secured to the movable contact support 17 so that the normal tendency of the spring 15 will be to draw the movable contact support 17 downwardly, or towards the coil 11.

20 Contact ring indicated at 18 is secured to the movable contact support 17, as clearly shown by Figure 1 of the drawings.

25 As clearly shown by Figure 1 of the drawings, the body portion is provided with a plurality of bores disposed longitudinally thereof, the bores being of diameters to accommodate the coiled springs 19, which springs are of the expansible type. These springs are arranged in predetermined spaced relation with respect to each other, in a circular line.

30 The movable contact support 17 is formed with a depending annular flange 20 inside of which the armature 21 moves. The armature 21 is mounted on the lower end of the rod 22, which is formed with a lower tapered section 23. The upper end of the rod 22 is threaded, and extends into the threaded opening of the disk 24.

35 Mounted within the shell or body portion 5, is a disk 24 that supports the split tube 25, the tube 25 being provided with slots extending inwardly from the lower end thereof, providing a plurality of fingers 26. These fingers are provided with heads 27 that contact with the inner surface of the depending annular flange 20, under normal conditions. The disk 24 is of a diameter to rest on the coiled springs 19 to the end that under normal conditions, the action of the springs 19 will be to urge the disk 24 upwardly. A disk of mica or similar insulating material is indicated at 28, and insulates the disk 24 from the springs 19.

40 45 50 55 55 The split tube 25 is of a diameter appreciably

larger than the diameter of the rod 22, providing a housing for the coiled spring 29 which normally acts to urge the disk 47 upwardly.

Pins indicated by the reference character 30 extend upwardly from the disk 24 and are adapted to be engaged by the cams 31 depending from the cap 32. These cams 31 are provided with straight end portions 33, so that when the cap is rotated to cause the cams to move the pins, the pins will snap from the cams at the straight ends thereof, for purposes to be hereinafter more fully described.

The disk 24 is also provided with an upstanding flange 34 to which the disk 35 is connected, the disk 35 providing the cover for the thermal element. The disk 23 is disposed between the cover disk 35 and thermal element 36, the disk 23 being shown as resting on the thermal element at all times. The thermal element embodies disks connected at their edges and formed with annular corrugations, and constructed of bimetallic or special alloy, thermo-magnetic material, which will bulge when the disk expands under heat, due to an abnormal condition in the circuit, with the result that the armature is drawn through the fingers, releasing the fingers 26 to the action of the coiled spring 19, which forces the movable contact support 17 and contact mounted thereon, away from the stationary contact 37, breaking the circuit.

The contact member with which the contact 18 cooperates in completing a circuit, is indicated by the reference character 37, and is in the form of segmental contacts against which the contact 18 engages. A wire indicated at 38 establishes the circuit between the solenoid coil 11 and stationary contact 37, the return circuit being made through the wire 39 that connects with the contact 37 at the opposite side thereof, the wire 39 being in circuit with the screw sleeve 7.

A stem indicated at 40 extends from the button 41 through the cover disk 35 and connects with the disk 23 that rests on the thermal unit 36.

Carried by the cap 32, is a ring 42 which is formed with a groove in its periphery, the groove accommodating the spring member 43 which is in the form of a split ring constructed to expand beyond the periphery of the ring 42 so that portions thereof will extend into the groove 44 formed in the shell or body portion 5, near the upper end thereof. This spring member allows the cap to rotate, but at the same time prevents the cap from moving longitudinally of the body portion.

Ring member 42 is prevented from rotating within the housing, by the lugs 45 that extend from the periphery thereof, and are seated in recesses formed in the inner surface of the shell or body portion 5.

It might be further stated that the stationary contacts 37 are prevented from rotary movement, by the lugs 46 that extend from the periphery thereof, and lie in recesses formed in the inner surface of the body portion 5.

The operation of the automatically controlled switch or circuit breaker is as follows: When the device is positioned in a fuse plug socket, the movable contact member is in the position shown by Figure 1 of the drawings. The cap 32 is now rotated in a clockwise direction resulting in the cams 31 directing a downward movement of the pins 30, disk 24 and split tube 25. Since the disk 47 supports the rod 22 and the coiled spring 29 is positioned between the disk 47 and heads 27 of the fingers 26, it will be seen that downward

pressure moves the rod 22 downwardly until the sleeve and rod 22 are in positions as shown by Figure 6 of the drawings. The heads 27 are now in expanded position below flange 20 due to the fact that downward movement of the disk 24 moves the free ends of the fingers over the tapered portion 49 of the armature 21. Upon further rotary movement of the cap 32, the cams move so that the pins 30 snap over the straight end portions 33 thereof. With this movement, the movable contact support 17 together with the contact ring 18, are moved upwardly since the contact support 17 has become connected with the split tube 25, whereupon, the contact ring 18 engaging the stationary contact segment 37, complete a circuit through the device.

Assuming that a short occurs in the circuit, the coil 11 will become energized resulting in the armature 21 being drawn downwardly. It will of course be understood that when the device is in its set position, the spring 15 will be placed under tension. As the armature 21 moves away from the fingers 26, the fingers contract due to the resiliency thereof, leaving the movable contact support 17, whereupon the coiled spring 15 snaps the movable contact ring 18 downwardly away from the contact member 37, breaking the circuit.

When the device is in a set position, and an overload occurs in the circuit, the coil 11 will become heated, causing the thermal element to expand. As the thermal element expands, the disk 47 is forced downwardly moving the rod 22 to a position where the tapered portion thereof disengages the fingers. With this movement, the coiled spring 15 contracts to move the movable contact ring 18 out of engagement with the stationary contact segment 37, again breaking the circuit.

It might be further stated that when it is desired to break the circuit, the button 41 is manually depressed, and when the device is to be reset, the cap 32 is rotated in a clockwise direction, as described.

From the foregoing it will be seen that due to the construction shown and described, the device may be readily and easily set for operation, after the line or circuit has been repaired, without the necessity of providing a new circuit breaker.

What is claimed is:

1. An automatically controlled circuit breaker comprising a body portion adapted to be screwed into a fuse plug socket of an electric circuit, a stationary contact member within the body portion, a movable contact member within the body portion and adapted to complete a circuit with the stationary contact member, a solenoid in the circuit with the contact members and mounted within the body portion, said solenoid including an armature embodying a stem formed with a cam surface, a movable member within the body portion, spring fingers carried by the movable member and normally engaging the cam surface, said fingers adapted to expand by movement of the fingers over the cam surface of the armature stem of the solenoid, connecting the movable member and movable contact member, means for moving the movable member whereby the movable contact member is moved into engagement with the stationary contact member, completing a circuit, and said solenoid adapted to disengage the fingers releasing the fingers when an abnormal condition occurs in the circuit, and means for operating the movable con-

tact member to disengage the stationary contact member, breaking the circuit.

2. An automatically controlled circuit breaker comprising a body portion adapted to be secured in a fuse plug socket of an electric circuit, a stationary contact member within the body portion, a movable contact member within the body portion, a support for the movable contact member, said support including an annular flange, a movable member mounted within the body portion and including spring fingers, adapted to extend to a position adjacent to the annular flange of the movable contact member, a solenoid within the circuit and including an armature stem having a cam surface formed thereon movable between the spring fingers and adapted to expand the spring fingers into frictional contact with the flange of the movable contact member support, means for moving the movable member and movable contact member whereby the movable contact member engages the stationary contact member completing the circuit, said solenoid adapted to be energized when an abnormal condition arises in the circuit, whereby the cam surface moves away from the spring fingers, releasing the movable contact member, and spring means for actuating the movable contact member to break the circuit.

3. An automatically controlled circuit breaker comprising a body portion adapted to be screwed into a fuse plug of an electric circuit, a stationary contact member and a movable contact member mounted within the body portion, a movable member above the stationary contact member, spring fingers carried by the movable member, a solenoid having a tapered armature stem mounted within the body portion the tapered portion of said armature stem adapted to extend between the spring fingers expanding the fingers into engagement with the movable contact member and connecting the movable member and movable contact member, said armature stem adapted to move between said spring fingers in one direction, releasing the fingers, when the solenoid is energized due to an abnormal condition in the circuit, and means for moving the movable contact member out of engagement with the stationary contact member breaking the circuit when the movable contact member is released by said fingers.

4. In a device of the character described, a body portion adapted to be screwed into a fuse plug of an electric circuit, a stationary contact member and a movable contact member mounted within the body portion, a latch adapted to normally hold the contacts together, said latch comprising a tube split longitudinally from one end, providing spring fingers, a solenoid in the body portion and embodying a tapered armature stem adapted to move between the spring fingers urging said spring fingers laterally into frictional engagement with the movable contact member connecting said movable member and said movable contact member, yieldable means adapted to move said movable contact member to a position closing a circuit between the movable contact member and stationary contact member, and said tapered armature stem adapted to move releasing said fingers and freeing said movable contact member when the solenoid becomes energized, and a spring adapted to move the movable contact member away from the stationary contact member breaking the circuit.

5. An automatically controlled circuit breaker comprising a body portion adapted to be screwed into a fuse plug socket, a stationary contact member including an annular flange, mounted within the body portion, a movable contact member mounted within the body portion and adapted to engage the stationary contact member completing an electrical circuit, a movable member extending through the movable contact member, said movable member embodying a tube split longitudinally providing a plurality of spring fingers, a solenoid within the body portion and in circuit with the contact members, a tapered stem forming a part of the solenoid and adapted to extend into the split sleeve expanding said fingers into frictional engagement with the annular flange holding the sleeve and movable contact together in a set position, said solenoid adapted to withdraw the said tapered stem, releasing the fingers, and a spring adapted to move the movable contact member away from said stationary contact member breaking the circuit.

JOHN HILMAR HELLAND.
